ALLEN A. FULLER, OF BIRMINGHAM, ALABAMA, ASSIGNOR TO FULLER ELEVATOR EQUIPMENT COMPANY, A CORPORATION OF ALABAMA.

AUTOMATIC SIGNALING MECHANISM FOR STARTING ELEVATORS.

1,253,807.

Specification of Letters Patent. Patented Jan. 15, 1918.

Application filed August 13, 1915. Serial No. 45,278.

To all whom it may concern:

Be it known that I, ALLEN A. FULLER, a citizen of the United States of America, residing at Birmingham, in the county of Jefferson and State of Alabama, have invented 5 certain new and useful Improvements in Automatic Signaling Mechanism for Starting Elevators, of which the following is a specification.

10 My invention relates to an automatic signaling apparatus for starting and controlling the movement of a battery of elevators and my object is to so design the apparatus that it is capable of ready adjustment to vary 15 the headway according to varying traffic conditions.

In Letters Patent No. 1,012,623 granted to me I disclosed a signaling apparatus for starting elevators in which the circuit controlling switches to the signal lights were disposed in the elevator shaft and designed to be mechanically adjusted by the elevator. This arrangement was subject to the objection of interposing mechanism in the elevator shafts and of subjecting such mechanism to operation by the rapidly moving elevators. Moreover it was impractical to adjust the switches to different floors to vary the headway on the cars for different traffic conditions during different times of the day.

According to my present invention I dispense with all car actuated switch mechanism and provide, preferably in the pent house, a switch mechanism for each cab 35 which is caused to move correspondingly with the movement of the elevator car which it controls and circuits controlled by this mechanism for flashing a signal lamp at the top and bottom of the elevator shaft for the 40 cab which such mechanism controls.

An important feature of my invention relates to the manner in which each switch mechanism may be adjusted to flash the light at the terminus its respective cab is approaching when at any desired distance therefrom, thus enabling the flashing of the signals to be accelerated or retarded and the headway of the cabs automatically varied either uniformly at each terminus or differentially at their termini so that the cabs would be started more quickly in one direction than in the other.

A further advantage of my present invention is that it reduces to a minimum the wiring for the elevator shafts and the mech-

anism is all disposed where it can be most conveniently observed and attended.

My invention further comprises the novel details of construction and arrangements of parts which in their preferred embodiment 60 only are hereinafter more particularly described, reference being had to the accompanying drawings which form a part of this specification, and in which:

Figure 1 is an end elevation of the switch 65 control mechanism showing the lighting circuits in diagram.

Fig. 2 is a vertical sectional view on the line $\alpha-\alpha$ of Fig. 1.

Fig. 3 is a detail sectional view of one of 70 the brush contacts; and

Fig. 4 is a diagrammatic illustration of the signaling apparatus applied to a plurality of elevator shafts.

Similar reference numerals refer to similar parts throughout the drawings.

In the preferred embodiment of my invention illustrated, I have mounted the same in a bracket frame 1 attached to the bearing 2 for the elevator drum shaft 3 but any other 80 suitable support may be provided. A small shaft 4 is attached to or driven by the drum shaft 3 and has mounted thereon a gear 5 which meshes with a gear 6 mounted to turn on a shaft 7 fast in the bracket 1. A collar 8 85 is interposed between the wheel and the bracket to suitably space the gear 6 and I attach to the gear by screws, rivets or any suitable means an insulating disk 9 of wood, fiber or any suitable material. The ratio of 90 the gears 5 and 6 is such as to give to the gear 6 a rotation slightly less than 360° in the travel of the drum shaft to raise or lower its cab from end to end of its shaft. Preferably the gear, responsive to the full movement of the cab, is caused to travel about 270°. The shaft 7 passes through this disk 9 with a clearance to reduce friction.

Mounted on the outer face of the insulation disk 9 is a contact plate 10 which is provided 100 with a central opening 11 made substantially larger than the diameter of the shaft 11 so as to avoid contact therewith. This contact plate 10 has two arc shaped openings cut therein concentric with the shaft 7 but disposed at different radial distances therefrom. In the outer opening, which forms a marginal notch in the plate, I mount an elongated arcuate plate 12 which throughout is spaced from and therefore insulated 105 110

from the contact plate 10 and is of less length than the notch. In the space left between one end of plate 12 and the adjacent end of the notch is a series of closely spaced segments 13 which are insulated from each other and the plates 10 and 12 and all are suitably attached to the insulating disk 9 by screws or rivets. I provide sockets 14 between the several segments 13 and between 5 each end segment and the plates 10 and 12, and these openings are adapted to receive contact plugs 15 which serve to electrically connect any desired number of the segments 13 in series to each other and to plate 16. 10 15 In like manner the inner arc shaped opening which forms a slot in the plate is provided with an arcuate plate 16 and with spaced segments 17, and also with sockets 14 and plugs 15. A switch arm 18 formed of fiber 20 or like suitable insulating material is mounted on the shaft 7 and has rigidly connected to it a collar 19 which is forced into frictional contact with the plate 10 by means of a coiled spring 20 surrounding the outer end 25 of the shaft 7 and compressed against the switch arm 18 by a nut 21.

Three contact brushes are mounted in the switch arm 18, one brush 22 being disposed to contact continuously with the plate 10 30 as the latter moves. The brush 23 is disposed to contact both with plate 10 and with the plate 16 and the segments 17, and the brush 24 is disposed to contact both with the plate 10 and with the plate 12 and 35 I provide the same number of segments 17 as there are segments 13, and I arrange the two sets of segments in radial alignment. Each of these brushes are preferably mounted as shown in Fig. 3, the brush being formed 40 by a cylindrical carbon brush which is inserted in an externally threaded copper sleeve 25 and held to its work by a coil spring 26 interposed between the top of the brush and a screw cap 27 on the sleeve. 45 The sleeve 25 is screwed down through an opening in the switch arm 18 and has threaded onto it a pair of nuts 28 and 29 which clamp between them the circuit wire for the brush. By this arrangement the 50 sleeve can be adjusted and also the tension of the brush.

On one end of the switch arm 18 I mount a pair of copper blades 30 and 31 which are insulated from each other and on the 55 rear end of the bracket I mount a pair of spaced clips 32 and 33 which are insulated from the frame and from each other by insulation 34 and are disposed to be engaged respectively by the blades 30 or 31, according to the direction in which the plate 10 is moving. The switch arm 18 controls two signals 35 and 36, one being disposed at the upper end and the other at the lower of the shaft for the cab operated by the same drum 60 shaft 3 as drives the contact plates under 65

such switch arm. A simple arrangement of the wiring system for each cab signals is shown and may be briefly described as follows: The positive line current from any suitable source of supply comes in over the 70 wire 37 to the light 35 returning to the clip 32. A branch circuit 38 leads from the wire 37 to light 36 and to the clip 33. The negative line wire 39 leads to the brush 22 and through it to the contact plate 10, which 75 is, therefore, always in circuit with this wire. A wire 40 connects the brush 23 with the switch blade 31 and a wire 41 connects the brush 24 with the blade 30. The operation for the control mechanism of a single 80 elevator cab may be briefly described as follows: The contact plate 10 will be first adjusted so that, for instance, the intermediate segment 13 will stand under the brush 24 when the elevator cab is, say five 85 floors distant from its lower terminus at which is located the light 35, and that as the cab approaches this terminus the plate 10 will be moved counter-clockwise. Of course the contacts may be set for any desired 90 floor but I am assuming the fifth floor as a suitable point for flashing the lower signal and the fifth floor from the top as the point for flashing the top signal which is provided for by the fact that the brush 95 23, which controls such top signal, will stand on a segment 17 corresponding to the segment 13 on which the brush 24 stands. Now assuming the contact plate 10 to begin moving counter-clockwise as the cab descends, the frictional contact between the sleeve 19 and the plate 10 will have swung the switch arm 18 to the left until the blade 30 engages the clip 32 so that the circuit to light 35 will be closed as soon as 100 the brush 24 is in electrical circuit with the plate 10. Obviously, the time such electrical circuit will be closed will depend upon the number of plugs 15 used as each plug 105 brings an additional segment 13 into circuit with the plate 10. As shown in Fig. 1 the light 35 will flash when the plate 10 moving counter-clockwise, the second segment 110 13 from the right passes under the circuit closing brush 24 which controls it and obviously the light will be held on after the brush engages plate 10 and until on the reverse movement of the car and of the plate 10 the circuit is broken at the clip 32 by the reverse or clockwise travel frictionally 115 imparted to the contact arm 18 which is thereupon swung over into engagement with the clip 33. The circuit to the lamp 36 will not be closed until the insulated plate 16 and the dead segments 17 shall have moved from 120 under the brush 23. In other words, as soon as it strikes a live segment (shown as next to the last segment on the left) which is plugged into circuit with the plate 10, it 125 will flash the light 36. Obviously by using 130

more plugs and increasing the live segments of each set the lights will be caused to flash when the cab is farther from its respective termini and the headway between cars is reduced and contrari-wise as the plugs are removed the headway increases, it being noted that the plugs must always be removed beginning with those nearest the plates 12 or 16. The plate 10 after frictionally throwing the switch arm 18 will continue to turn and will frictionally hold the switch against one or the other of the clips 32, 33. The plugs and segment retaining screws are preferably disposed out of the path of the brushes.

15 It will of course be understood that a similar signaling equipment is provided for each elevator cab of the battery and that all are adjusted similarly. It follows therefore that as the cars A and B, see Fig. 4, approach their respective termini they will flash signals which can be observed by the operator in the cab at each terminus and will direct him to start, as such signal indicated to him that another car is a given 20 distance from such terminus. This signal is held lighted until the cab starts away from it when it is quickly cut out. The dotted lines indicate equal subdivisions of the shaft and there may be one or more floors to each 25 subdivision. By manipulating the plugs 15 the headway can be reduced between maximum conditions of travel and increased to the desired extent at other times. Obviously the segments may be continued to nearly encircle the plate 10 and the length of the 30 insulated or dead plates 12 and 16 may be decreased. Also the plugs may be manipulated to vary the headway of cars leaving one terminus from that at which they leave 35 the other terminus, it being often desirable, as when the building is filling during the morning hours, to move the cars quickly from the top to return them the sooner to the bottom for a load, and vice-versa during 40 the late afternoon hours when the heavy travel is down. The apparatus is extremely flexible and yet is so simple it will wear indefinitely and requires no skilled operator to set it as the segment can be numbered 45 and directions for inserting plugs charted by the building superintendent and by him varied as experience dictates.

Having thus described my invention, what I claim as new and desire to secure by Letters Patent, is:—

50 1. An automatic signaling mechanism for starting elevators, comprising electrically controlled starting signals at the termini of the elevator shaft; a circuit breaker mechanism for each elevator comprising a primary switch means controlled by the reversals in direction of movement of the elevator, and a secondary switch means controlled by the position of the elevator, signal circuits 55 including the said switches and starting sig-

nals, and contact means to vary at will the circuit closing positions of the secondary switches.

2. An automatic signaling mechanism for starting elevators comprising electrically controlled starting signals at the termini of the elevator shaft, signal circuits, and switch control mechanisms for said signal circuits, one of which mechanisms is operably connected to and movable responsive to the speed and direction of travel of each elevator cab, each switch mechanism comprising primary switch means, responsive to a reversal in the direction of movement of its respective cab, to open the circuit connections to a signal at the terminus departed from and to close at such switch the circuit connections to the signal at the terminus being approached, and adjustable switch means responsive to the position of the cab, to complete the closing of circuit closed at its primary switch when the cab is at a predetermined distance from said latter terminus, said means being adjustable to vary the distance from which a cab operates the signal it is approaching.

3. An elevator cab, a shaft in which it travels, signals at each terminus of said shaft, signal control mechanism operatively connected to the cab and movable back and forth responsive to the movements of the cab, said mechanism comprising two series of normally insulated contacts, a line circuit, means to connect one or more of the contacts of each series to one side of said circuit, a brush for each series of contacts, a connection from each brush to one of a pair of insulated switch blades, circuits each including one of said signals and leading to the other side of said line circuit, terminals for said signal circuits disposed to be engaged by one or the other of said switch blades, according to the direction of travel of the cab and to automatically open circuit the signal at the terminus last departed from, and to close the circuit from the other signal to its respective brush.

4. A starting signal control mechanism for elevators comprising a controller arm carrying a pair of insulated brushes, a contact plate rotatably mounted and comprising two series of insulated contact segments flush therewith, one set being disposed to contact with one brush and the other set with the other brush, means to produce a frictional engagement between the controller arm and plate to shift the arm on each reversal of direction of movement of the plate, switches controlled by the reverse movements of said arm, circuits controlled by said switches and leading each to a different terminus of the cab shaft, a signal in each circuit, and circuit connections to said contact plate, means to connect up one or more of each series of segments with said plate,

and means to drive the controller with the cab through a speed reducing drive.

5. The combination with an elevator cab, and signals at each end of its termini, of circuits from said signals leading to a control mechanism, the control mechanism comprising a rotatable disk and a rotatable switch arm, means to hold said arm in frictional engagement with the disk, a speed reducing driving connection between the cab and the disk, a pair of insulated brush contacts on the arm, a line circuit, a series of insulated contact segments for each brush, means to connect one or more of each set of segments into circuit with one side of the line circuit, a circuit through each signal to the other side of the line circuit, a reversing switch means controlled by the frictional movements imparted to said switch arm for controlling the circuits through the segments and brushes to said signal circuits.

6. In a signaling mechanism for starting elevator cabs, a revolute disk, an elevator drum shaft, speed reducing gearing adapted to rotate said disk not in excess of 360° during the complete travel of the drum shaft in either direction, a switch arm mounted concentric with the disk, means holding said arm in frictional engagement with the disk, insulated brushes carried by said arm, a number of normally insulated plates on said disk, which plates are disposed to travel under each of the brushes, means to connect a variable number of the plates for each brush in series with one side of the line circuit to vary the percentage of the disk's travel during which the brushes will be in circuit with the line circuit, and a reversing switch to which said brushes are connected and which is frictionally reversed upon the reversal in the direction of the rotation of the disks, signals at each elevator terminus, and signal circuits connected to the other side of the line circuit and adapted to be closed by said reversible switch to the brushes, substantially as described.

7. A starting signal controller mechanism for elevators comprising a multiple contact plate, a driving means from the elevator hoist to said plate, two series of insulated segments mounted on said plate, a reversible switch comprising a movable switch arm frictionally engaging said plate, insulated brushes on said arm and arranged to simultaneously engage each with its respective set of contacts, a circuit to the initial contact of each series, means to connect up one or more of the segments of each series in series with its respective initial segment, starting signals at each end of the elevator shaft, and two signal circuits leading from said signals to opposite sides of said reversible switch, and circuits from said brushes

to said reversible switch, the initial segment of each series being so disposed that one brush approaches such segment of its series as the other brush departs from its respective initial segment.

8. In a signaling mechanism for starting elevator cabs, a circuit controller mechanism comprising a switch arm and a multiple contact plate which are relatively movable responsive to movements of a cab, said plate carrying a series of segments normally insulated, means to connect a variable number of said segments in series with an initial segment, means to connect said initial segment to the line circuit, a signal, and a signal circuit adapted to be closed through said switch arm and contacts, substantially as described.

9. In combination, a movable element driven by an elevator, two sets of normally insulated contacts on said element, sockets between the segments of each row, contact plugs insertible in said sockets to connect segments, a brush for each set of segments which are disposed to engage the brush during the elevator travel between its termini, starting signals at said termini, circuits between said brushes and signals, a reversible switch interposed in said circuits, and line circuits connected to the initial contact of each series and to said signal circuits, substantially as described.

10. Mechanism for automatically signaling the several elevators of a battery of elevators for controlling the starting of same, comprising, in combination, a common signaling means for the whole battery of elevators located at a terminus thereof and comprising a number of separate signals, one controlled by each elevator and each so disposed as to signal all elevators at said terminus, and means controlled by the position and directional movement of an elevator to operate its respective signal and signal its position relative to said terminus to all other elevators at said terminus, said means comprising a speed reducing driving connection between each elevator and its respective control means, substantially as described.

11. In a mechanism for automatically signaling the elevator cars of a battery of elevators for controlling the starting of same, the combination with a series of elevator cars and their shafts, of a main line circuit, a pair of branch circuits for each car, a switch for each car controlled by the directional movement of said car and arranged to connect either of the respective branch line circuits to said main line, a signal in each branch line circuit, said signals being located at each terminus of the elevators and being arranged to form a common signaling means at said termini for the whole series

of elevators, and switch means in each branch line circuit controlled by the position of its respective car and comprising a movable switch arm and a contact means correlated therewith and variable in length to cut its respective part of the common signaling means into and out of service when

its respective car is at any desired distance from its termini, substantially as described.

In testimony whereof I affix my signature. 10

ALLEN A. FULLER.
